masking can be regulated by the tension of the rubber during the winding operations. Typically suitable winding tensions may be, for example, 4 to 6 oz. for rubber cord $\frac{1}{2}$ " in diameter.

The thus-masked rod is then sandblasted, or otherwise treated as shown in FIGURES 11 and 12, to remove all of the photosensitive material and conductive metal overcoating not masked by masking means 8 and lying on the raised portion of the treated rod 2. The masking means 8 are then removed from the rod to leave a series of individual photocells, i.e. one photocell in the bottom of each group, along the full length of the threaded rod. Each of these photocells as shown in FIGURES 13 and 14 comprises spaced electrode portions formed by the metallic overcoating 6 with the exposed photosensitive layer 4 therebetween.

If desired, all of the cells may be provided with a common connection along one side of the assembly. This may be accomplished by, for example, the application of silver paint or other suitable conducting means connecting all of the cells along one side.

FIGURES 15 to 17 also show a preferred arrangement for making contact with individual cells. The arrangement, as illustrated, includes a wire comb made up of a series of highly conductive spring wires 10, typically beryllium/copper wire having a silver overcoat, embedded in a block 12 of suitable non-conducting plastic such as polymethylmethacrylate or the like. Each of the wires 10 is adapted to rest in the bottom of a groove for contact with one of the electrodes 6 of the photocell. Such contact is preferably completed by means of additional conductive metal, e.g., silver paint, representing an extension 14 for each electrode. This extension may be provided for during the overcoating operation, as indicated heretofore, or by the application of silver paint or the like after the overcoating. Subsequent sandblasting removes all of such additional metal except for the masked extensions in the bottom of the grooves. As a further alternative, the extension may be formed by suitably painting the grooves with silver or the like after the sandblasting operation.

As shown, the opposite free ends of the wires are so formed as to permit making connections with auxiliary equipment. It will be recognized that this arrangement makes it possible to have individual contacts for practically any number of photocells, regardless of how closely spaced the cells may be, since the free ends of wires 10 can be bent or deformed as desired to make whatever auxiliary connections are necessary.

It is particularly desirable in practicing the method de- 45 50

scribed herein to subject the rod coated with photosensitive material to ionic bombardment prior to application of the overcoating metal. Typically, such bombardment may be carried out for a period of about 30 seconds to 5 2 minutes using a pressure of the order of 1 mm. of mercury. Other conditions normally employed in carrying out ionic bombardment may also be used. Such bombardment allows considerable control and modification of the final electrical characteristics of the photocells described herein. For instance, it has been found that ionic bombardment reduces the light-on resistance of the photocells by a factor of 10 over the untreated cells and does not seriously affect the dark resistance.

It will be appreciated that the photocells described herein have a variety of uses. Typically, the present photocell units are useful in the textile industry for the purpose of regulating or controlling the feed of fabric undergoing treatment. It will also be understood that various modifications may be made in the invention described herein without deviating from the scope thereof as set forth in the following claims, wherein I claim:

1. A multiple photocell unit comprising a ceramic rod having a plurality of transverse grooves extending the length thereof and an individual photocell in the bottom of each of said grooves, each photocell being electrically insulated from adjoining photocells and comprising a layer of photosensitive material and a pair of closely and transversely spaced opposed conductive metal layers overlying at least a portion of the photosensitive material layer.
2. A multiple photocell unit according to claim 1 wherein said grooved rod is a threaded rod.
3. A multiple photocell unit according to claim 1 including means for contacting said cells, said means comprising a non-conductive block having a plurality of conductive metal wires connected thereto and each of said wires contacting one of said photocells.
